The ornamental design for a vertical take-off and landing aircraft, as shown and described.

DESCRIPTION

FIG. 1 is a perspective view showing the top, left side and front of a vertical take-off and landing aircraft with the wings and tail thereof extending horizontally,

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof;

FIG. 7 is a rear elevational view thereof;

FIG. 8 is a perspective view showing the top, left side and front thereof with the wings and tail extending vertically;

FIG. 9 is a top plan view thereof;

FIG. 10 is a left side elevational view thereof;

FIG. 11 is a bottom plan view thereof;

FIG. 12 is a right side elevational view thereof;

FIG. 13 is a front elevational view thereof; and,

FIG. 14 is a rear elevational view thereof.

The broken lines showing parts of the aircraft depicts environment and forms no part of the claim.
